Application May 29, 1936, Serial No. 82,390
 In Germany June 1, 1935

10 Claims. (Cl. 179—18)

The present invention relates to a circuit arrangement for subscribers' lines in telephone systems provided with freely hunting switches and more particularly preselectors. It aims at rendering false calling conditions at the subscribers' lines inoperative as regards their effect on the hunting switches in such systems.

False calling conditions can be produced on account of the completion of loops of subscribers' lines or connecting lines. They can also occur during the establishment of a connection or during the releasing operations. In the first case the calling condition produced when setting up a call may be recognized as false if a subscriber after initiating a call delays for a definite period before completing the call. The second case occurs when in systems in which the release of a connection is dependent upon the calling subscriber, the final selector becomes released before the called subscriber has replaced his receiver.

For the purpose of rendering inoperative the false calling conditions occurring in all these cases the arrangement according to the invention produces a circuit arrangement which does not involve any further expenditure of switching means at the subscribers' lines and without using special constructional means.

This is achieved in that a two-stage relay brought under the influence of the subscribers' line through the operation of a releasing impulse transmitted when a false calling condition is set up, which relay when partially energized serves to respond to the call when the latter is initiated, is held fully operated when a false calling condition is set up and prevents this calling condition from becoming effective in the freely hunting switch.

It may be noticed that the arrangement can be applied to freely hunting switches of various constructions for example preselectors or group selectors especially since in the case of group selectors the free selection is similar to that effected by preselectors.

The drawing represents one embodiment of the invention. The invention is, however, not to be considered to be limited to this embodiment. T_n represents a subscriber's station which has access to outgoing lines over the preselector VW. One of these outgoing lines is represented by L_{a1} , L_{b1} and L_{c1} . The preselector possesses four wipers which are indicated by sa , sb , sc and sd . The wiper sd serves to return the preselector to the rest position. To contact 11 in the contact bank of the testing wiper sc a relay G is connected which is common to several preselectors

and which controls a time switch which temporarily opens contact $9k$. It is not necessary to point out the object of this operation as it forms no part of the invention. A two-stage line relay R having windings I, II and III, is associated with the subscriber T_n at his connecting line. Cut-off relay T having windings I and II is connected to the subscriber's line and serves as a testing relay. When energized in its first stage (winding I) relay R operates only the contact $8r$. When fully energized i. e. over winding III the relay operates contacts $5r$, $6r$ and $7r$. Winding II of relay R serves as a locking winding and maintains the relay energized in the second stage.

When the subscriber at the station T_n initiates a call the following circuit is established on the removal of the receiver: earth, battery, resistance W_1 , contact $1t$, lead L_{a1} , loop at the subscriber's station T_n , lead L_{b1} , contact $2t$, winding I of relay R , contact $5r$, and earth. In this circuit relay R energizes in the first stage. It accordingly operates contact $8r$ so that the following stepping circuit is established for the preselector: earth, battery, wiper sd , position O of wiper sd , contacts $8r$, $3t$, $7r$, rotary magnet DVW, interrupter RU and earth. The rotary magnet DVW is energized impulsively in this circuit. When the preselector finds a free line for example the line L_{a1} , L_{b1} , L_{c1} , shown, the following testing circuit is set up: earth, battery, wiper sd , contact $8r$, windings II and I of relay T , winding III of relay R , contact $6r$, wiper sc , lead L_{c1} , contact $10tr$ of a thermal relay TR , switching means (not shown) in the subsequently arranged switching devices, relay TR , and earth. In this circuit relay T energizes while the current flowing through relay TR heats the thermostatic element associated therewith, to cause the operation of contact $10tr$ after a predetermined time. By switching over contact $4t$ the testing circuit is maintained. By the switching over of contact $3t$ the stepping circuit is broken and thus the preselector is brought to rest. In the circuit just mentioned relay R becomes fully energized over its winding III. It then operates contacts $5r$, $6r$ and $7r$. This, however, does not produce any particular switching operation.

It may be mentioned that a meter can be arranged in parallel with winding I of relay T .

If the subscriber now operates his calling device to operate the switching mechanism connected to line conductors L_{a1} , L_{b1} , L_{c1} , the initial movement of the switch closes contacts $on1$, which remain closed as long as the switch is off.

normal, to short circuit relay TR and to thereby prevent the opening of contacts 10tr.

If the subscriber does not continue the further establishment of the connection within a given period, for example, by delaying the dialling operation, the contact 10tr is momentarily opened. This has the effect of breaking the circuit passing over wiper sc and winding I of relay T. Relay T releases and returns its contact to the normal position. The switching over of contact 3t does not, however, establish the stepping circuit for the preselector since contact 1r is still open. On the return of contacts 1t and 2t to the rest position the following circuit is established: earth, battery, resistance W1, contact 1t, lead La, loop at the subscriber's station Tn, lead Lb, contact 2t, windings I and II of relay R and earth. In this circuit relay R remains fully energized. Contacts 5r, 6r and 1r are accordingly in the working position. The line originally seized is again accessible to general traffic since the seizing circuit is broken at contacts 4t and 6r.

The subscriber can now be given a signal in any known manner indicating that he has become disconnected. When he replaces his receiver relay R returns to normal and contact 1r reestablishes the stepping circuit, whereupon the preselector is advanced until its wipers have reached the rest position, i. e., when wiper sd reaches contact O. Testing during the return to the rest position is prevented by the fact of contact 8r having been opened on the release of relay R.

It will be assumed that on initiating a call on the part of subscriber Tn all the outgoing lines are engaged. In this case the preselector is advanced to position 11. In this position the following circuit is established: earth, battery, wiper sd, contact 8r, windings II and I of relay T, winding III of relay R, contact 6r, wiper sc, position 11 of wiper sc, the common relay G, contact 9k and earth. In this circuit relay T energizes and switches over its contacts. In addition relay R is energized completely. Relay G connects up a device which causes contact 9k to be transitorily opened. This causes relay T to release so that relay R is brought under the influence of the calling station by way of its windings I and II. Relay R is maintained energized completely over the subscriber's loop so that the testing circuit is broken at contact 6r and the stepping circuit is broken at contact 1r. The preselector accordingly remains in position 11 until the calling subscriber replaces his receiver and thus releases relay R. Guarding of contact 11 does not take place during the disconnecting condition on account of the opening of the testing circuit at contacts 4t and 6r. When the subscriber replaces his receiver the preselector returns to the normal position in the manner already described.

The arrangement illustrated can also be used in systems in which the release of a connection is effected by the calling subscriber in such a way that the final selector also is returned to normal. Assuming that subscriber Tn is called a circuit is established over the incoming testing line Lcn which passes over resistance W1, wiper sc in its rest position, contact 6r, winding III of relay R, windings I and II of relay T, wiper sd, battery and earth. In this circuit relays T and R are energized. Relay T energizes before relay R so that no stepping circuit is established over contacts 8r and 3t. If the release is effected by the calling subscriber the earth connected to the lead Lcn is disconnected in any known manner. Relay T accordingly deenergizes. Relay R which is con-

structed as a slow to release relay does not yet release, but remains energized over the subscriber's loop of the called subscriber Tn. No stepping of the selector takes place since the stepping circuit which is prepared by contact 8r remains broken at contact 1r. When the subscriber replaces his receiver relay R is deenergized and contacts 8r, 1r, 6r and 5r return to normal.

What is claimed is:

1. In an automatic telephone system, an automatic switch having access to a plurality of trunk lines, a cut-off relay and a two-step line relay in said switch, means responsive to the initiation of a call for operating said line relay in its first step, means controlled by said line relay in its first step to operate said switch to find an idle trunk line, means for operating said line relay in its second step and also said cut-off relay when an idle line is found, and means for automatically deenergizing said cut-off relay while holding said line relay fully operated in the event that dialling over the seized trunk line is delayed.

2. In an automatic telephone system an automatic switch having access to trunk lines, a two-step line relay in said switch, means responsive to the initiation of a call for operating said line relay in its first step, means controlled by the operation of said line relay in its first step for controlling the operation of said switch to hunt for an idle trunk line, means for operating said line relay in its second step when an idle trunk line is found, a cut-off relay in said switch, said cut-off relay operated responsive to the selection of a trunk line to extend the calling line thereto, means in said trunk line automatically operated in case the subscriber delays dialling for releasing said cut-off relay and for maintaining said line relay operated, and circuit connections controlled by the restored cut-off relay and operated line relay for rendering said trunk line accessible to other switches and locking said calling line out of service.

3. In an automatic telephone system, a subscriber's line circuit including a line relay and a cut-off relay individual thereto, an automatic switch operable responsive to the operation of the line relay when a call is initiated over the line for extending said line, a timing device associated with said switch effective in the event the calling subscriber delays dialling, said line relay arranged to operate part way only pursuant to the initiation of a call, means for operating said line relay fully when the cut-off relay operates in response to the extention of the line, and means responsive to the operation of said timing device and depending upon said line relay having been operated fully when the line is extended to lock the subscriber's line out of service.

4. In an automatic telephone system, a subscriber's line circuit including an automatic switch individual thereto having a cut-off relay and a two-step line relay, means responsive to the initiation of a call for operating said line relay in its first step to control the operation of said switch to find an idle trunk line and extend the call, means for operating said cut-off relay and for operating said line relay in its second step when the switch finds an idle trunk, means in said selected trunk line effective in case the subscriber fails to dial over the trunk line for de-energizing said cut-off relay, and means for maintaining said line relay fully operated over said line circuit and to release said trunk line for service and lock out said line circuit from service.

5. In an automatic telephone system as

claimed in claim 4 in which the operating circuit for the switch is controlled jointly by the cut-off relay and the line relay and the circuit is prevented from being effective when the line 5 is locked out of service by the restoration of the cut-off relay and the operation of the line relay, said line relay arranged to be slow acting and held operated over the subscriber's line after the cut-off relay restores.

10 6. In an automatic telephone system as claimed in claim 4 in which the testing circuit for the switch in its operation of hunting an idle trunk line is controlled jointly by the cut-off relay and the line relay in its first step, said 15 testing circuit rendered ineffective responsive to the deenergization of said cut-off relay and the full operation of the line relay over the line circuit at a time when the line circuit is locked out.

7. In an automatic telephone system as 20 claimed in claim 4 in which the line circuit is also accessible to incoming calls, means for energizing said line relay initially in its second step and said cut-off relay responsive to an incoming call, means responsive to the release of 25 the incoming call for deenergizing said cut-off relay, and means for maintaining said line relay fully operated over said line circuit after said cut-off relay deenergizes, said line relay arranged to be slow acting so as to remain operated during 30 the interval in which the cut-off relay restores and connects the line relay to the line circuit.

8. In an automatic telephone system as 35 claimed in claim 4 in which the line relay is arranged to be slow acting and is provided with a plurality of windings, one of said windings serving

to energize the relay in its first step when a call is initiated, and another winding serving to energize the relay in its second step when the call is extended.

9. In an automatic telephone system, a subscriber's line circuit including an automatic switch individual thereto having a cut-off relay and a two-stage line relay, means responsive to the initiation of a call for operating said line relay in its first stage, means controlled thereby 10 for operating said switch to find an idle trunk line to extend the call, means responsive to the switch encountering an idle trunk line for operating said cut-off relay and for operating said line relay in its second stage, means for operating 15 said switch to a particular position in case all trunks are busy, and means connected to the said particular position on which the switch stops for deenergizing said cut-off relay, said line relay remaining fully operated over the line circuit to 20 lock out the line from service.

10. In an automatic telephone system as claimed in claim 9 in which the line relay in its second stage controls the circuit of the switch for testing the condition of the trunk lines and 25 also the operating circuit of the switch, means responsive to the full operation of said line relay when the particular position of the switch is reached and all trunk lines are busy for disconnecting the testing and operating circuits of the 30 switch, and means for deenergizing said line relay responsive to the disconnection of the calling subscriber and for restoring said switch to normal position.
